UNITED STATES PATENT OFFICE.

IRA DONOVAN BRILL, OF MARLINTON, WEST VIRGINIA.

DOOR LOCK.

Application filed July 6, 1921. Serial No. 482,779.

To all whom it may concern:

Be it known that I, IRA D. BRILL, a citizen of the United States, and resident of Marlinton, in the county of Pocahontas and 5 State of West Virginia, have invented certain new and useful Improvements in Door Locks, of which the following is a specification.

One object of my invention is to provide 10 a simple form of lock for doors having comparatively few elements and in which some of the parts may be of stock form.

The invention consists in the features and combination and arrangement of parts hereinafter described and particularly pointed 15 out in the claims.

In the accompanying drawings—

Figure 1 is a vertical sectional view 20 through a portion of a door longitudinally along the knob spindle and knobs.

Fig. 2 is a horizontal sectional view taken longitudinally along the latch.

Fig. 3 is a face view of a part of the door.

Fig. 4 is an edge view of the door and associated parts.

Fig. 5 is a detail view similar to Fig. 1 but with the parts in a different position.

Fig. 6 is a detail view, showing the spindle in transverse section, and the locking means 30 therefor.

Fig. 7 is a view of a detail.

In these drawings, 1 indicates the door which is mortised and recessed to receive the latch casing 2. The latch 3 is simply mounted within this casing and is pressed outwardly by a spring 4 contained in a recess 5 in the latch, said spring bearing at its front end against the wall of the recess and at its rear end against an abutment 5' which is 40 fixed to the casing. The latch is connected by a flexible member such as a chain 7 with the collar 8 mounted on the knob spindle 9 which latter is of generally rectangular form in cross-section and fits within a corresponding opening in the operating member 8. When the knob is turned in either direction the latch will be retracted against the pressure of its spring by the turning of the collar or rotary member 8 which will cause 45 the flexible connection 7 to draw the latch back. The latch casing is provided with a suitable detent or lock member for holding the latch in its forward position as will be described hereinafter and this detent member is pivoted at 10 to the latch casing and 50 is provided with a forwardly extending arm 60

11 which ordinarily lies to one side of the edge of the latch so that the latter may be freely retracted. The detent is normally pressed into this position by a spring 12. 60 The detent has one end at 13 projecting through the side wall of the latch casing for a purpose hereinafter described. The knob spindle 9 has on its opposite ends, as in usual practice, the knobs 14 and 15 one of which 65 14 is secured thereto by screw in the ordinary manner. These knobs may be of substantially stock form, modified however, as hereinafter mentioned. The spindle passes through a collar or member 16 which is 70 mounted in a plate 16' fixed on the inner side of one of the escutcheon plates 17, in the present instance this being the escutcheon plate which is on the outer side of the door. This member 16 has 75 radially extending pins 18 to extend into a groove, recess or slot 19, Fig. 6, formed in the knob spindle and these pins are borne upon by other pins 18' which are mounted in the plate 16' carried by the escutcheon 80 plate. The pins 18' are pressed inwardly by springs 21 held in recesses in the plate 16', these springs being held in place by any suitable means at the outer ends of the recesses such as plugs 22. The pins 18 are 85 controlled by a controlling bar 23 slidably mounted in the knob spindle and having a finger button 24 at the end thereof, this finger button lying coaxially with the inner knob and projecting from the face thereof. 90 When this controlling bar is pressed all the way inwardly by pressure exerted upon the finger button forcing the latter toward the knob on the inside of the door as in Fig. 1, portions of this controlling bar will have a 95 cam action on the inner ends of the pins 18 and these pins will be forced outwardly against the pressure of the spring pins 18' until the joint or line of separation between the pins 18 and the spring pins 18' register 100 with the line of division or the joint between the rotary collar 16 and the surrounding plate 16' so that with the parts in this position the knobs can be turned to turn the spindle 9 and retract the latch for the opening of the door and this action will take place by a turning movement of either knob in either direction. In this action the pins 18' will offer no obstruction to the turning of the collar or rotary member 16 because, as 110 above stated, the ends of these pins will register with the line of separation at the

point 18*. If, however, the controlling bar is displaced from the position above described by grasping the finger button 24 at the inside knob and pulling this away from the knob, the cam portions of the controlling bar will be withdrawn from the inner ends of the pins 18 and then, supposing the parts to be in normal position with the pins 18 registering with the pins 18', the springs 21 will force the pins 18' inwardly and these pins will cross the line of separation between the rotary collar 16 and the plate 16', see Fig. 6, and therefore turning of the spindle will be prevented because of the locking action of the pins 18'. In this locked position of the parts, however, the door may be opened by the use of a key 25 such as shown in Fig. 5, which will be inserted through a keyhole 26 in the outer knob so that the inner cam shaped end of this key will engage between the inner ends of the pins 18 and will force these pins outwardly so that the inner ends of pins 18' will be brought into registration with the crevice or line of separation between the rotary collar 16 and the surrounding plate 16'. In other words, the action of the key upon the pins will be the same as the action of the inner end of the controlling bar upon the pins, when this controlling bar is in its normal inward position. Under these conditions, the knob with its spindle can be turned because the pins 18' will then offer no obstruction and the latch will be retracted to open the door.

35 The controlling bar may be retained in its several positions by any suitable detent means and as one form of such means, I provide in the wall of the spindle suitable notches as indicated at 27 to be engaged by a detent projection 28 on the controlling bar or rod. I provide means by which the door may be locked and prevented from being opened from the outside even with the use of a key, and this is accomplished in a simple manner by giving to the controlling bar an additional step movement such as will make its detent projection 28 register with the outermost one of the notches 27 in the spindle. In other words, this movement is an additional step over that necessary to lock the parts as above described. When the controlling bar is given this additional outward step movement by pulling upon the finger button 24 a washer or suitable member 20 mounted on the spindle and operated by the movement of the controlling bar through the projection 29 will be brought against the projecting end 13 of the detent 11, forcing this end inwardly and causing the end or arm 11' of the detent to be thrown in, or to one side so as to bring it into line with a shoulder 30 on the latch. This will prevent the latch from being retracted, and it will be noticed that as this locking of the latch in

its advanced position takes place by means of the detent 11, 11' and entirely independent of the locking parts above described involving the pins 18, 18', the use of a key inserted through the keyhole of the outer 70 knob will be ineffectual because it cannot in any way act upon the parts which now are effecting the locking action, namely the detent 11, 11' and the projection or washer 20. I thus provide a safety lock device so 75 that the person within the room can lock the door and prevent it from being unlocked by the use of any sort of key which may be inserted in the keyhole of the outer knob.

It will thus be seen that I provide a controlling bar which in its normal inward position in respect to the inner knob will control the locking devices such as pins 18, 18' to allow free operation of the latch and when it is drawn one step outwardly 85 will lock the knob spindle against operation, but will permit unlocking of the parts by the insertion of the key on the outer side of the door, and when an additional step movement is given to the controlling bar 90 by pulling upon the finger button, the lock will be set to prevent its unlocking from the outside of the door by means of the key. Any suitable arrangement of the pins 18 may be employed. They may be of different lengths in different locks, or arranged in different numbers or in different locations in respect to the knob spindle so that a great number of permutations would be 95 secured.

In the case where the device is used as a night latch it may be thrown out of action during the daytime, for which purpose the knob would be turned to retract the latch and in doing this the spindle will make a 105 half turn and when this is accomplished, by drawing the controller bar outwardly, the locking pins 18' will engage the recesses in the rotary collar 16 diametrically opposite those which they cooperated with when 110 the parts were locked with the door closed, at which time, of course, the latch is projected. In other words, the latch may be locked either in its outer or inward position by suitably manipulating the knob and the 115 controlling bar in a certain relation to each other.

The key may be formed with a recess 25' to receive a projection on the controller bar and for getting various permutations this 120 projection may be of different sizes, shapes or locations. The same is true of the shoulders or cam surfaces at the end of the controlling bar which acts on the pins 18.

Reverting to that condition of the lock 125 resulting from pulling the controlling bar to its extreme outward limit and thus causing the latch to be locked in its outermost position, or in other words, with the parts in safety position, so that the lock cannot be 130

operated by the key from the outside of the door, it will be understood that the occupant of the room cannot lock himself out, because, should he set the lock in the above 5 position while the door is open he then will be unable to close the door because the latch will be locked in its outermost position.

The occupant of the room cannot set the lock in safety position unless the door is first 10 closed and he is within the room.

It will be seen that I utilize a substantially ordinary latch member as a locking bolt. This latch has a beveled face which coacts with a suitable guard or keeper by 15 which the latch will be retracted by a camming action and will snap into place within the keeper if the door is pushed to, and provided, of course, that the detent 10, 11 is not set at the safety position by drawing the 20 controller rod all the way out to its extreme limit.

Where, therefore, I refer to a locking bolt in the appended claims, this is to be interpreted to mean either a latch form of bolt 25 or an ordinary form of bolt.

Fig. 7 shows that the washer 20 is provided with projections 20^x which enter the longitudinal recess in the spindle so that contact can be made with the shoulder on 30 the controlling bar by which the collar is operated.

The knob 15 is secured to the spindle by two rivets or screws 15^x which leave the key way free through the center of the spindle.

35 The sides of the spindle may be connected also by a cross pin 23^x which also will act as a guide for the controlling bar.

The screw 23^a will also serve this purpose. 40 This screw and pin pass through slots in the controlling bar. The sides of the controlling bar are sufficiently resilient in respect to each other at the portions adjacent the knob 14 as will permit the detent 27 to operate properly. The latch is preferably 45 provided with a recess in its side to receive the end of the detent.

I claim:

1. A lock for a door comprising a spindle, a locking bolt, a spindle to pass through the

door, a connection between the spindle and 50 the locking bolt for retracting it, locking means to prevent rotation of the spindle, and a slotted controlling rod extending from the said locking means to the inside of the door, 55 said controlling rod being movable longitudinally of the spindle, in one position setting the spindle locking means to prevent rotation of the spindle, in a second position releasing the same, and means operated by the controlling rod when set in a third position 60 for locking the bolt independent of the spindle lock, substantially as described.

2. In combination in a lock for doors, a bolt, a rotary spindle passing through the door, a connection between the rotary spindle and the bolt for retracting the latter when the spindle is rotated, a slotted member movable lengthwise of the spindle and projecting at the inner side of the door to be operated by the occupant of the room, 65 and means for engaging and locking the bolt against retraction when the controlling member is set in a certain position, said means consisting of a washer surrounding the spindle and engaged by a portion of 70 the controlling rod to be moved thereby along the spindle and a detent to engage the bolt operated by said washer, substantially as described.

3. A door lock including a bolt, a casing 80 therefor, a rotary spindle for retracting the bolt, a member movable longitudinally of the spindle operable from without the lock, means engaging said bolt to prevent retraction, said means being mounted upon the 85 casing and operated by said longitudinally movable member.

4. A lock including a bolt, a rotary slotted spindle for retracting said bolt, means to prevent rotation of said spindle, a key insertable from one side of the door to render ineffective said rotation preventing means, and a member located in the slot in said spindle and means operable by said member to prevent retraction of the bolt by 90 said key.

In testimony whereof I affix my signature.
IRA DONOVAN BRILL.
